(57) CLAIM

The ornamental design for a hot beverage appliance, as shown and described.

DESCRIPTION

FIG. 1 is a front perspective view of a hot beverage appliance showing our new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken lines in the drawing depict portions of the hot beverage appliance that form no part of the claimed design.
